Gerald T. Baldwin
ATTORNEY.

UNITED STATES PATENT OFFICE.

HARLEY M. JOHNSON, OF RIVER ROUGE, MICHIGAN.

AMPLIFIER.

Application filed November 13, 1924. Serial No. 749,724.

My invention relates to improvements in amplifiers.

It is an object of the invention to provide an amplifier into which the sound waves enter through two downwardly inclined diverging passages having the lower ends of their adjacent sides connected by means of a wall substantially parallel with the amplifier base, and having the lower end of their outer sides flared inwardly, as it is found that by this construction that a full even tone is obtained. The uniform increase in the cross sectional area insures even amplification, and the opposing sound waves deflected in two directions result in a purity of tone.

Another object of the invention is to provide an amplifier consisting in part of an eddying or equalizing chamber not directly in line with the flow of the sound waves by means of which blasting can be almost entirely eliminated.

A further object of the invention is to provide an amplifier so constructed that when applied to phonographs, and particularly to portable types, considerable space can be saved on account of the fact that the motor may be placed within the amplifier without in any way affecting the volume or quality of the sound.

With these and other objects in view, which will be pointed out as the description proceeds, the invention consists in certain novel construction and combination of parts hereinafter more fully described with the aid of the accompanying drawings.

Figure 1 illustrates a front elevation of a portable phonograph with the motor arranged inside the amplifier.

Figure 2 is a side elevation.

Figure 3 is a plan view.

Figure 4 shows a plan with the top of the amplifier removed, and

Figure 5 is a detail.

In the drawings the amplifier 1 is shown within a portable phonograph, 2 indicating the casing of the latter and 3 the lid.

The upper wall of the amplifier consists of a main portion 4 onto the underside of which the motor 5 is attached as by screws 30, and a portion 6 which carries the tone arm support 7. The latter portion 6 is partly supported by a diagonal strip 22 glued to the underside of the main portion 4.

The connector 8 which extends downwardly

from within the support 7, connects the latter with the throat 9, from which extend downwardly the inclined diverging passages 10 and 11, the adjacent sides 12 and 13 of which have the transverse wall 14 secured to their lower edges. The wall 14 is substantially parallel with the base 15 of the amplifier.

The lower outer edges 16 and 17 of the passages 10 and 11 project below, and are curved inwards towards, the transverse wall 14. The sound waves are discharged through outlets 19 in the front panel 18 of the amplifier.

In the construction shown in the drawing, wherein one inclined passage is at right angles to the front panel 18, I utilize a curved wall 20 to further aid in throwing the sound waves forward.

The amplifier is preferably located partly above and partly below the joint between the casing 2 and the lid 3. The reason for favoring this arrangement is in order to facilitate the installation of an upwardly curved front portion 21 of the base 15, which projects forwardly beyond the front 18. This upwardly curved portion, the top of which terminates below the top of the front 18, is of assistance in completely blending the sound waves particularly in the case of small sized machines. 24 is an opening through the side of the amplifier through which the winding spindle 23 extends.

The base 15 is securely fastened on the sides, front, and rear of the casing 2 in which it is contained, but has nothing in direct contact with it intermediately of its length or width. The front 18 and the curved wall 20 terminate at their lower edges just above and out of contact with the said base.

25 designates the upper portion of the amplifier, which constitutes an equalizing or eddying chamber by which sudden extremes of sound are modified, and blasting almost entirely eliminated, the large volume of the space therein having a tendency to retard the outward flow of sudden outbursts of sound.

The downwardly inclined diverging passages 10 and 11 are preferably made of very thin material such as heavy bristol board treated on both sides with shellac, and the transverse wall 14 is generally fastened to the adjacent sides 10 and 11 by rivets 26,

which pass through one of the said walls and also through lugs 27 integral with the transverse wall 14.

In the foregoing the invention has been described and shown as applied to a portable phonograph. It is obvious however that it can with very slight modifications be applied to a large cabinet phonograph wherein the tone arm support is located substantially centrally and towards the back of the machine. In that case the downwardly inclined diverging passages would still be arranged one on each side of the motor.

Again the invention may be used for other purposes, independently of phonographs, such as radio amplification.

And while in the foregoing the preferred embodiment of the invention has been described and shown, it is understood that the construction herein described is susceptible to alterations and modifications provided the said alterations and modifications fall within the scope of what I claim.

What I claim is:

1. In a sound amplifier, the combination of a throat member, downwardly inclined diverging passages open on their undersides dependingly connected to said throat member, a transverse wall supported by the inner adjacent sides of said diverging passages towards their lower ends, said transverse wall forming the top of a lower chamber into which both of said passages discharge, and a front having sound discharge openings.

2. In a sound amplifier as described in claim 1, the combination wherein the sound discharge openings extend above and below the transverse wall.

3. In a sound amplifier as described in claim 1, the combination wherein the outer sides of the inclined passages extend below the transverse wall and are curved inwardly at their lower ends.

4. In a sound amplifier as described in claim 1, the combination wherein the transverse wall is spaced from the sides of the amplifier so that communication is afforded between said lower chamber and an upper chamber the underside of which latter is bounded by said transverse wall.

5. In a device of the character described, the combination of sound amplifier having a throat member mounted thereon, downwardly inclined diverging passages open on their undersides dependingly connected to said throat member, a transverse wall supported by the inner adjacent sides of said diverging passages towards their lower ends, said transverse wall forming the top of a lower chamber into which both of said passages discharge, a front having discharge openings therethrough, a motor dependingly arranged in said sound amplifier, said motor terminating above said transverse wall, and a spindle driven by and forming part of said motor extending through the top of said sound amplifier.

HARLEY M. JOHNSON.
